UNITED STATES PATENT OFFICE.

WILLIAM M. SCHLESINGER, OF PHILADELPHIA, PENNSYLVANIA.

ELECTRIC RAILWAY.

SPECIFICATION forming part of Letters Patent No. 339,018, dated March 30, 1886.

Application filed November 24, 1885. Serial No. 183,870. (No model.)

To all whom it may concern:

Be it known that I, WILLIAM M. SCHLESINGER, a subject of the Queen of Great Britain, residing at Philadelphia, in the county of Philadelphia and State of Pennsylvania, have invented certain new and useful Improvements in Electric Railways, of which the following is a specification, reference being had therein to the accompanying drawings, where-

10 in—

Figure 1 is a diagram showing line of electrical conductors, one of which is made up of disconnected or insulated sections, safety devices for said sections, a feeding-conductor for the 15 safety devices, a generator, and an electrical indicator and circuit-connections to the safety devices, all arranged in accordance with my invention. Fig. 2 is a diagram showing one of the conductor-sections, a preferable form 20 of safety device, indicator, and its circuit-connections to the safety device. Fig. 3 is a plan of detail modification, and Figs. 4, 5, and 6 are detail plans of modifications of safety devices and circuit-connections with the indicator-box.

25 My invention has relation to line circuits or conductors for electric railways or for other purposes, and has particular reference to that form of railways wherein one or both line-30 conductors are divided into sections and each section provided with a current safety device, so that when the electrical condition of any one or more of the sections becomes faulty or defective the excess of current passing to the 35 faulty section will cause the safety device to act to cut the section out of the line-circuit, and thereby prevent the safety of traffic or continuity of travel of the whole line being endangered by such faulty or defective section; and it has for its object to automatically 40 locate a defective or faulty section after it has been cut out of the line-circuit, in order that it may be quickly repaired. To accomplish this result I provide one or more indicator-

45 boxes at the generator or other stations located along the line of way, and provide for connecting each section or its safety device with a separate call or marked drop-plate in the indicator-box, so that when an excess 50 of current passes to a section and operates its

safety device to cut the section out of the line-circuit the safety device will also act to close or interrupt the circuit to the individual call or plate for said section in the indicator-box, and thereby automatically locate the 55 faulty section, so that the repair or line men can go to it and repair it without imposing upon them the labor of hunting up such faulty section.

60 My invention accordingly consists of a line-circuit having sections, each of which is provided with a safety device, a feeding conductor or conductors for the safety devices, an indicator-box, and circuit-connections between the safety devices and the indicator-box, as 65 hereinafter set forth and claimed.

In the drawings, A represents a line of railway; B, the cars having electric motors and traveling connections with the line-conductors C C', of any of the well-known or other forms. 70 One of the conductors, C', is divided into disconnected or insulated sections c, and each section is provided with a current safety device, D, in circuit with a feeding-conductor from generator E by way of wire C', all of 75 which may be variously constructed and arranged as described and shown in an application for United States Letters Patent filed by me of an even date herewith, and I do not herein confine myself to any particular division 80 of the line-conductors into sections, nor to the safety devices and their feeding-conductors.

85 At a suitable point or points along the line of way, preferably at the generator or working-station, I locate an indicator-box, F, having suitable calls or drop-plates, f, equal in number to the conductor-sections of the line. f' is a battery for the indicator, having feeding-conductor f², which passes to all the safety 90 devices on the line, and from each of these devices is a separate return-wire, f³, for the individual call or drop plate in the indicator-box.

95 In the drawings, more plainly shown in Fig. 2, I have illustrated an open circuit, f⁴, between the battery feed-wire f² and the return-wires f³, the terminals f⁵ of which are in the line of movement of a movable lever or part, g, of the safety devices, so that when an ex- 100

cess of current causes any one safety device to act to cut a conductor-section, *c*, to which it is applied, out of the line-circuit the movable lever *g* will be moved by its retracting-spring 5 to contact with the electrodes or terminals *f*⁵ to complete the battery-circuit through the individual call in the indicator-box for the cut-out section, and thus locate it to the attendant at the working station.

10 Instead of fixed contact-points *f*⁵, a spring-contact may be used, as shown in Fig. 3, to complete circuit to wire *f*⁵ of box F.

In the drawings I have shown the form of safety device having two pivoted right-angle levers, *g* *g*', having retracting-springs *g*² *g*³, and armature *g*⁴ for magnet *g*⁵, and contact-plate *g*⁶, with circuit-connections, as fully described and shown in my aforesaid application; but I do not limit myself to any particular form of 20 safety devices, as a fusible flexible strip safety device of the well-known form or other constructions of the same may be employed; nor do I limit myself to the manner shown and described of making circuit through the indicator-battery when the safety devices act to cut out a conductor-section, as it is obvious that such circuit may be made or interrupted to sound the alarm in various ways without departing from the spirit of my invention.

25 30 Again, while I have described the indicator applied to railways having sectional line-conductors, I do not limit myself thereto, as the indicator may be used in connection with any of the now known constructions of line-conductors for locating faulty insulation or defects in the line.

I have shown some of the many forms of safety devices that may be used in Figs. 4, 5, and 6 of the drawings.

40 In Fig. 4 the fusible strip safety device is illustrated both for sectional line-conductor and for the indicator-box. In this case the current passes from *C*² to binding-post *d*, fusible strip *d*', and binding-post *d*' to section *c* of line-conductor *C*'. Strip *d*' is of such thickness that it melts on the passage of a current exceeding a certain fixed limit. Below this strip *d*' is another strip, *d*³, of fusible material, fixed between binding-posts *d*⁴ *d*⁵ and very 45 close to but not touching strip *d*'. Strip *d*³ is 50 in circuit with battery and indicator-box wires *f*² *f*³, as shown. As soon as strip *d*' melts, through a too heavy current passing to section *c*, the strip *d*³ is fused by the spark, interrupting the current of battery *f*' to allow 55 the number in the indicator-box for said section to fall down.

In the form shown in Fig. 5 the current for the section passes from *C*² around the magnet *g*⁶ in and to its armature support or lever *g*¹¹ to a contact-pin, *g*¹², and thence to section *c*. The lever *g*¹¹ is held in contact with pin *g*¹² by a spring, *g*¹³. At the outer end of lever *g*¹¹ is 60 an insulated metal pin or plate, *s*, having connection *s*' with battery-wire *f*², and below which is a flexible contact strip or point, *s*²,

in circuit with indicator-box wire *f*³. The contact-strip *s*² is normally away from lever-strip *s* when the desired or normal current is passing to section *c*. In line with the end movement of strip *s* is a spring-catch, *s*³. If the current passing to section *c* is not in excess of that desired, the parts of the safety device assume the position shown. If, however, the current exceeds this limit, the attraction of magnet *g*⁶ exceeds the force of spring *g*¹³ and its armature is attracted to move lever *g*¹¹ downwardly. The metal strip *s* then snaps into catch *s*³, and is held there until manually released, the current through 75 contact *g*¹² is broken and the contact between strip *s* and point *s*² is made to complete the battery-circuit through the indicator-box for the drop or signal of section *c*.

In Fig. 6 the battery *f*' and its wire *f*² is 80 dispensed with, and a single fusible strip, *d*', is used between section *c* and its feeding-wire *C*². In this case the indicator-box F is in a shunt of high resistance from the dynamo E, and if the current to section *c* is interrupted by the fusing of strip *d*' the current through its drop or signal in the indicator-box is also interrupted. When the indicator box is so located, either the fusible strip or magneto safety devices, as shown, may be 90 used.

What I claim is—

1. An electric line-circuit having disconnected or insulated sections of wire or circuit, safety devices with feeding-conductors 100 for said sections, in combination with an indicator-box having an individual call or indicator for each said section, and circuit-connections between the safety devices and indicator-box, substantially as set forth.

2. A line-circuit having safety devices for different points along the same, separate feeding conductor or conductors for the safety devices, in combination with an indicator, and circuit-connections between the indicator and 110 safety devices, substantially as set forth.

3. An electric railway having a line-circuit, disconnected or insulated sections in said circuit, safety devices with feeding-conductors for said sections, and connection between 115 the safety devices and an indicator-box, substantially as and for the purpose set forth.

4. A line-conductor having a section provided with safety device having a feeding-conductor, which device acts by excess of current to cut said section out of the line-conductor, in combination with an indicator attachment which is operated by the safety device simultaneously with the cutting of the section out of the line-conductor, substantially as 120 set forth.

5. In combination with an insulated section or point of a line-circuit, a safety device having a feeding-conductor, circuit-connections, and an indicator, and operating by excess of current passing through it to simultaneously cut said section out of the line-cir- 130

cuit and produce an automatic operation of the indicator for denoting that the section is cut out of the line of circuit, as set forth.

6. In an electric railway, a line-conductor divided into sections, current safety devices for said sections, and feeding-conductor for the safety devices, in combination with an indicator box or alarm, and circuit-connection

through the safety devices to indicator-box, substantially as and for the purpose set forth.

In testimony whereof I affix my signature in presence of two witnesses.

WILLIAM M. SCHLESINGER.
